HANDBAG WITH INNER PIVOTALLY
ALIGNED PURSES

Benjamin Roth, Bridgeport, Conn.

Application January 6, 1948, Serial No. 720

3 Claims. (Cl. 150—29)

1

This invention relates to handbags, and more particularly to the inner purse construction of said bags.

An object of the invention is to provide an improved handbag having a pair of individually openable inner purses which are mounted as a pivotal unit and arranged to be compact and occupy a minimum of space in the handbag and to provide for easy access to the interior of the bag, and wherein the purses are disposed in distinctly different and separate locations in the handbag and constitute essentially distinct and separate units even though connected with each other, thereby to enable each purse to be readily independently opened and closed without interference from the other purse, and to be readily distinguished from the other so as to greatly facilitate the selection of the desired purse. By this organization one inner purse may be conveniently used to carry bills, and the other to conveniently carry loose change, resulting in a very handy and advantageous arrangement.

Pivottally mounted inner purses have found wide acceptance in the past, due to the fact that the advantageous high mounting of the purse enables it to be readily opened and closed since such mounting maintains the purse in an accessible position, and due to the fact that the pivotal mounting does not adversely affect the accessibility of the contents of the handbag.

Attempts have been made to provide a plurality of pivotally mounted inner purses whereby one such purse may be used for bills and the other used for loose change, or whereby the purses may be used for other different articles which are to be kept separate. However, the structure by which this was accomplished resulted in the inner purses being secured close together and broadside to each other whereby they both constituted in effect a single unit and lost their individuality, so to speak, so that it was not especially easy or convenient at all times to select, and to open or close the desired one of the purses. Prior to this invention it was felt to be necessary to have each purse extend completely across the interior space of the handbag in order that the purses would be securely and properly supported and held, and therefore the arrangement involved locating the purses broadside and substantially coextensive with each other, and required that the openings of the purses be located side-by-side closely adjacent each other. Thus it was not particularly easy, especially to the point of being almost automatic, to select the desired purse at any time, and also it was not feasible, for example, to pro-

2

vide purses having the same type of closing devices such as hinged frames which snapped closed and opened.

In an attempt to overcome these disadvantages it was proposed to mount two inner purses of the hinged frame type in end-to-end relationship against one inner wall of the handbag, the purses being carried by one of the main frame members of the bag. However, by doing this, the advantages of the pivotal mounting of the purses were lost, and the symmetry of the bag when closed was lost; also, the purses were not as convenient to the reach.

According to the present invention the difficulties and disadvantages set forth above are overcome by the provision of a novel inner purse structure or frame so arranged that a pair of inner purses may be mounted end-to-end and substantially in alignment with each other and may both be carried on an inner frame which is pivotally mounted on the center portion of the main frame of the bag, preferably on the trunnions or pintles for the main frame.

Thus the purses may be disposed in distinctly separate locations, functioning as separate units even though connected with each other, and each purse need not be unduly large and extend entirely across the interior space defined by the main handbag section.

The inner frame or structure by which this is accomplished may comprise a pair of separate frame member each having generally a U-shape, with one leg of each member connected together, the members lying generally in a single common plane. The frame members may be secured together with both in an upright position, or with one in an inverted position, or both may be in inverted position.

According to the organization provided, the inner purses may be both of the snap-clasp hinged-frame type, or of the Zipper type, or folded flap type, one only of the purses may be of the type having a Zipper fastener, or of the type having folded flaps secured in place by snap fasteners, or of the billfold type. In each instance, the inner purses are disposed so as to be in distinctly separate locations, apart from each other, even though interconnected and therefore the desired one of the purses may be very easily and readily selected without likelihood of confusion and without difficulty, and operation of any one purse, to open it or close it may be accomplished without the slightest interference from the other.

In a specific form of the invention illustrated

3

herein, the inner frame structure has two frame units, one including a hinged member cooperable with a complementary hinged member to provide the well-known snap-clasp type of hinged-frame purse. The other frame unit is rigidly connected to the one unit, and is in the form of a U-shaped channel strip which is pinched or clamped over the edges of an inner purse or pocket assembly having a Zipper fastener. In this construction, the Zipper-operated purse is provided with at least one relatively stiff side wall which contributes to the rigidity of the U-shaped channel member, and the overall rigidity of the entire inner frame structure. The other or channel frame unit may carry a billfold type of purse, or a folded flap type of purse, and if desired a pocket or slide may be secured to the stiff side of the purse structure to carry an identification card or the like.

In all of the above organizations both of the inner purses are mounted in end-to-end relationship regardless of the type of closing means or specific purse structure, and are pivotally carried within the handbag and swingable as a unit to enable the contents of the handbag to be readily accessible, while at the same time enabling the inner purses to be distinct and separate, and easily selected and used.

Other features and advantages will herein-after appear.

In the accompanying drawings:

Figure 1 is a top view of an improved handbag made in accordance with the invention, the bag being open to show the interior or inner purse construction.

Fig. 2 is a vertical sectional view taken on line 2-2 of Fig. 1.

Fig. 3 is a vertical sectional view like Fig. 2 but in perspective, and showing another embodiment of the invention.

Fig. 4 is an elevational view of the novel inner frame structure provided by the invention.

Fig. 5 is a vertical sectional view of a handbag made in accordance with the invention and illustrating still another embodiment thereof.

Fig. 6 is a view like Fig. 5 but illustrating yet another embodiment of the invention.

Fig. 7 is a vertical sectional view in perspective of a handbag illustrating still another embodiment of the invention, and

Fig. 8 is a view like Fig. 7 but illustrating a further embodiment of the invention.

Referring to Figs. 1 and 2, the improved handbag of this invention comprises a main bag section 10 having sides 11 and 12, and ends 13 and 14. The main bag section 10 is secured to an outer frame comprising cooperable complementary frame members 15 and 16 which are of U-shape, the said members having hinge eyes 15a and 16a at their ends, receiving pintles 17 whereby the frame members are pivotally or hinged connected together. The frame members 15 and 16 may have any usual type of snap-clasp means, such as the cooperable clasp parts 15b and 16b.

According to the present invention a novel and improved inner purse structure 18 is provided for disposition within the main bag section 10 and for mounting on the outer frame members 15 and 16, the said structure including inner pockets or purses 19 and 20 which are mounted in end-to-end and aligned relationship and are pivotally carried as a unit to extend across the interior space of the handbag. The purses 19 and 20 are disposed in distinctly different and separate locations in the handbag, as is clearly shown in Figs.

4

1 and 2, and therefore constitute essentially separate and distinct units even though they are connected with each other at adjacent ends. As a consequence, the purses 19 and 20 may be very easily and readily distinguished from each other, and one or the other may be selected without chance of confusion and practically automatically, and each purse may be opened and closed separately from the other and without the slightest degree of interference being experienced. Moreover, since the two purses are pivotally movable as a unit they may be easily swung to one side or the other of the handbag to provide easy access to the main bag section. An extremely advantageous structure is thereby provided, and the purse 19 for example may be used to hold bills and the purse 20 used to hold loose change, or vice versa, or the purses may be used to hold other different articles which it is desired to keep separate.

In accomplishing the above desirable and advantageous location and mounting of the purses 19 and 20 a novel inner frame structure 21 is provided by the invention, Figs. 1 and 4, the said frame structure comprising a pair of U-shaped frame members 22 and 23 having legs 24 and 25, which are rigidly connected together, as by short posts 26, the latter being preferably of spherical shape as shown to enhance the appearance of the frame structure.

The U-shaped member 22 may be of the type commonly employed in the snap-clasp hinged-frame type of purse, and may be associated with a cooperable or complementary U-shaped frame member 21, thereby to provide a suitable support and operating device for the purse 20. The frame members 22 and 23 may have the usual form of clasp device 28, and may be secured together at one pair of corresponding ends by the pintle 17 and at the other pair of corresponding ends by a pintle 29.

The U-shaped frame member 23 is preferably of channel cross section as shown in Fig. 3, and is secured to the frame member 22 in upright position with respect to the member 22, which latter may be considered as in an inverted position as seen in Fig. 4. The channel frame member 23 is rigidly secured to the remaining one of the pintles 17, and this may be accomplished by providing an angular extension 17a on the pintle, which is welded or otherwise secured to the member 23.

By this construction the frame members 22 and 23 together constitute a rigid unitary frame structure which is pivotally carried by the outer frame members 15 and 16 of the handbag and which may be swung about a pivotal axis coincidental with the hinge axis of the outer frame members.

The purse 19 may be of the Zipper type, having a Zipper fastener 30 and may be secured to the channel frame 23 by having its edge portions inserted in the space between the sides of the channel, whereupon the channel sides may be forced together to pinch or clamp the edge portions of the purse. The purse 19 may be formed of two side walls 31 and 32, and preferably the wall 31 is made relatively stiff whereby it reinforces the frame member 23.

Thus the entire inner purse structure 18 constitutes a relatively rigid unit by virtue of the rigid connecting posts 26 together with the inflexible frame members 22 and 23 plus the stiff purse wall 31, and the entire structure may be readily swung about the pintles 17 toward one side or the other of the main bag section 10,

thereby enabling articles carried in the bag section to be easily and quickly removed.

Another embodiment of the invention is shown in Fig. 3, wherein parts similar to those shown and described in connection with Figs. 1 and 2 have been given like characters. In Fig. 3 the channel frame member 23 carries a purse 33 which has a boxlike shape, and which may be opened or closed at its top by a Zipper fastener 34. The shape of the purse 33 is such that it may readily accommodate a pack of cigarettes, box of matches etc., and thus a desirable combination may be had whereby money may be carried in the purse 20 and smokers' articles in the purse 33, to provide for a maximum of convenience for the user.

Another embodiment of the invention is shown in Fig. 5. In this figure the purse 19 may have secured to the stiff side 31 thereof a frame or pocket 35 which is open at the top and which may hold an identification card 36.

Still another embodiment of the invention is shown in Fig. 6, wherein the snap-clasp hinged-frame purse 20 is connected with an other snap-clasp hinged-frame purse 36. For this arrangement the frame member 22 of the purse 20 is connected with a companion frame member 37, both members being U-shaped and rigidly secured together by the spherical connector posts 26. The frame member 37 has a cooperable or complementary frame member (not shown) to which it is pivotally secured by pintles 38 and 39, the pintle 39 also forming the hinge pin for the frame members 15 and 16 of the main bag section. The frame of the purse 36 has the usual snap-clasp 40 as shown.

Fig. 7 illustrates another embodiment of the invention wherein the Zipper purse 19 has secured to its rigid side 31 a billfold 41 having portions 42 and 43 folded on and overlying one another, the said portions having a snap button fastener 44 whereby they may be held in folded relationship or released and spread apart.

Yet another embodiment of the invention is shown in Fig. 8 wherein the channel frame 23 carries a purse 45 having a folding flap 46. The purse 45 may have a frame or pocket 48 which is open at the top to enable an identification card 49 to be inserted therein.

It will be seen that in each of the embodiments of the invention illustrated herein the inner purses are disposed in end-to-end relationship and in alignment with each other, and are carried in distinct and separate locations within the main bag section 10 of the handbag, and the said inner purses are pivotally carried and swingable as a unit to provide for easy access to the interior of the main bag section. Also, although the purses are connected rigidly together at their adjacent ends, one or the other of them may be easily and quickly selected and opened or closed without interference from the associated purse. Both of the inner purses are thus mounted in the handbag so as to be readily accessible, and are pivotally carried in a high position in the bag and centrally thereof whereby they do not disturb or impair the symmetry of the main bag section 10 when the latter is closed.

Variations and modifications may be made within the scope of this invention and portions of the improvements may be used without others.

I claim:

1. In a handbag, a main bag section forming an interior space, said bag section having a mouth which may be opened to reveal the bag interior; a pair of inner purses having individual frame members connected in end-to-end relation; means connected with the main bag section for mounting the inner purses in end-to-end aligned relationship within the said interior space, said means enabling the purses to be pivotally swung as a unit about an axis extending substantially midway between the sides of the bag section when the mouth thereof is opened, thereby to provide for easy access to the contents of the main bag section; and means including frame members cooperable with said first-mentioned inner purse frame members and first-named means, to provide snap-clasp hinged-frame opening and closing devices for both of said purses.
2. In a handbag, a main bag section forming an interior space, said bag section having a mouth which may be opened to reveal the bag interior; a pair of inner purses having individual frame members connected in end-to-end relation; means connected with the main bag section for mounting the inner purses in end-to-end aligned relationship substantially midway between the sides of said mouth within the said interior space, said means enabling the purses to be pivotally swung as a unit about an axis extending substantially midway between the sides of the bag section when the mouth thereof is opened, thereby to provide for easy access to the contents of the main bag section; and separate closing means for each purse, at least one including a frame member pivoted to the inner frame to provide a snap-clasp hinged-frame opening and closing device for one of said purses.

3. In a frame for a handbag comprising a pair of U-shaped outer frame members having the ends of the legs of the U pivoted together to form a rectangular opening when the frame members are moved about their pivots; the improvement of providing an inner frame member disposed within the outer frame members and comprising a pair of individual U-shaped purse frames in end-to-end relation, said purse frames having the adjacent legs of the frames rigidly connected together and the other legs of each frame carrying a pivot aligned with and connected to the pivot for the outer frames whereby a rigid inner frame swingable on the pivotal axis for the outer frame members is provided.
